VIBRATING MECHANISM

Application filed November 15, 1928. Serial No. 319,511.

This invention pertains to vibrating mechanisms, such as are used to impart vibrating movement to concentrator tables and the like.

One of the objects of this invention is to provide a vibrating mechanism adapted to impart an oscillating movement which is quicker in one direction than in the reverse direction.

Another object is to provide such mechanism which will produce an oscillating movement in which the reversal of movement at one end of the travel is more sudden than at the opposite end.

Another object is to provide such mechanism by which the amplitude of the oscillating movement may be adjusted in a simple manner.

Another object is to provide such a movement which will be self-lubricating throughout.

Another object is to provide such a movement suitably housed so as to prevent the accumulation of dirt therein.

Another object is to provide such mechanism which shall be very rugged in construction and reliable in service.

Further objects will appear from the following description, taken in connection with the accompanying drawings, in which—

30 Figure 1 is a plan view of a mechanism embodying this invention, with the cover of the housing removed so as to disclose the interior parts;

Figure 2 is a section on line 2—2 of Figure 1; and

Figure 3 is a diagram illustrated the nature of the movement imparted by this mechanism.

In the operation of concentrator tables in which granular material is handled for the purpose of separating the various ingredients thereof, the nature of the movement imparted to the table is of great importance. The stratification of the material on the table and its movement along the table are very sensitive to changes in the nature of the movement, such as the rapidity of movement in each direction, as well as the suddenness of reversal at the end of each stroke. In most cases it is desirable to provide a movement which will

be more rapid in one direction than in the other and in which a sudden reversal takes place at the end of one stroke while a more gradual reversal occurs at the end of the opposite stroke. The mechanism of this invention is designed to produce such difference of speed, as well as a difference in the suddenness of reversal at the opposite ends of the travel.

Referring to the drawings, 1 designates a casing or housing, which also provides a support for the mechanism. The casing 1 may be provided with side flanges 2 provided with suitable bolt holes 3 for fastening the same to a suitable base, such as a concrete footing. Mounted in bearings 4 on the casing 1 is a drive shaft 5 having fixed thereto, outside the casing 1, a pulley or other suitable driving element 6. The shaft 5 has fixed thereon an eccentric 7, which in turn carries a roller 8. The roller 8 has a broad face, as shown in Figure 1, and is formed with openings 9 in its periphery, which communicate with inwardly directed spiral channels 10 extending to the inner bore of the roller. These channels are intended to catch a certain quantity of the oil contained in the casing 1 which is splashed up during the operation of the device and convey the same to its inner bearing on the eccentric 7 so as to lubricate said bearing.

Mounted in bearings 11 on the casing 1 is a pivot shaft 12. The shaft 12 has pivoted thereon a lever 13 provided on one side of the pivot 12 with a concave face 14 adapted for engagement with the cam roller 8 and at its other end with a clamping socket 15 adapted to receive a bar 16 and to clamp the same therein. The lever 13 is provided with a trough 17 adapted to collect oil splashed up during operation and to convey the same through an opening 18 to the shaft 12 to lubricate the same.

The bar 16 is a short, heavy bar clamped in the socket 15 and extending vertically upwardly from the arm 13. This bar has clamped to its upper end a bracket 19 having bearings 20 for a pivot pin or shaft 21. The bracket 19 also has a trough 22 adapted to collect the splashed oil which is conveyed

through an opening 23 to the pivot pin 21 to lubricate the same.

Fixed to the arm 13 adjacent the socket 15 is an adjusting screw 24. This screw passes through a perforation in the bracket 19 and is adjustably secured thereto by nuts 25 and 26. The screw 24 extends in parallel relation to the bar 16 and is adapted for the adjustment of the bracket 19 along said bar, such adjustment being obtained by manipulation of the nuts 25 and 26. The proper adjustment having been obtained, the same may be fixed by clamping the bracket between said nuts. Upon fixing such adjustment, the bracket 19 is, of course, securely clamped to the bar 16 by means of the clamping stud 27. The positions of the bar 16 and the screw 24 in parallel relation with one another and spaced from one another, also provide a construction which forms, in effect, a rigid beam extending between the lever 13 and the bracket 19. This beam is subjected to cross bending stresses during the operation of the mechanism, and the relative positioning of the elements 16 and 24 is such as to cause them to share the stresses involved. The arrangement is such that the stresses placed upon these two members are more in the nature of tensile or compressive stresses than cross bending stresses. Accordingly, a strong and rigid construction is thereby obtained.

Fixed to the ends of the pivot pin 21 is a yoke 28 provided with a screw socket 29 adapted for threaded engagement with a tension bar 30. The bar 30 is thus adjustably connected with a yoke 28. A nut 31 is provided to secure the bar 30 in adjusted position. The bar 30 is attached to the device to be oscillated, usually a concentrator table, not shown in the drawings. In accordance with the usual practice, the concentrator table is tensioned so as to exert a pull on the bar 30. This arrangement is illustrated in diagrammatic form in Figure 1, in which 32 represents a portion of the frame or support of the table, 33 a bar connected to the moving part of the table, 34 a spring bearing at one end against the part 32 and at its other end against a nut 35 on the bar 33. The spring 34 provides the tension which moves the table rearwardly after a forward stroke in response to the pull of the bar 30.

The casing 1 is adapted to be filled with lubricating oil about to the level of the line A. One end of the casing is provided with a perforation 36 through which the bar 30 passes out to the concentrator table. This perforation is large enough to permit the necessary vertical adjustment of the bar 30 and is closed by an adjustable closure plate 37 secured by screws 38 or the like. The casing is divided into two compartments by a transverse partition 39. This serves not only to strengthen the casing, but also provides that any dirt which may enter through the open-

ing 36 will be caught in the right-hand compartment and not permitted to contaminate the oil in the other compartment. Fins 40 on the sides of the casing may be arranged to collect the splashed oil and convey the same to the bearings 4 of the main drive shaft. The cover 41 of the casing is provided with a locking lug 42 adapted to take under a lug 43 on the casing. At the other end of the cover, a pair of lugs 44 extends downwardly on each side of a lug 45 on the casing so that when a suitable lock 46 is locked through perforations 47 in the lugs 44, said lock will, in cooperation with the lug 45, prevent the removal of the cover, the lugs 42 and 43 preventing the disengagement of the opposite end of the cover. In this way the mechanism is secured against tampering or unauthorized adjustment.

In the operation of this mechanism, the shaft 5 being driven from any suitable source of power, the rotation of the cam 7 will cause the roller 8 to roll along the concave face 14 of the lever 13. This movement will cause the lever 13 to rock on the pivot shaft 12 in response to the rotation of the cam 7. The bar 16 forms with the lever 13 a bell crank which causes a horizontal oscillation of the pivot pin 21 in response to the oscillation of said bell crank. This movement of the pin 21 causes a corresponding longitudinal oscillation of the bar 30 and the concentrator table or other device connected thereto. Assuming rotation as indicated by the arrow B, it will be noted that the down stroke of the lever 13 takes place during rotation of the shaft 5 through the arc C. This causes a movement of the pivot pin 21 from the point D to the point E. The return movement of the lever 13 takes place during the rotation of the shaft 5 through the angle F, which causes a return movement of the pivot pin 21 from D to E. It will be noted that with a uniform rotation of the shaft 5, the return movement takes place much more quickly than the forward movement. The diagram of Figure 3 illustrates the nature of this oscillation. In this diagram the ordinates represent travel of the bar 30 while the abscissæ represent time intervals. It will be noted that the reversal at the point G is much more sudden than that at the point H, while the travel from H to G is much more rapid than that from G to H.

It will be seen, therefore, that this invention provides an oscillating mechanism of very rugged construction which is easily adjustable and which may be adapted to various types of oscillating movements. The length of the bar 16 between the pivots 12 and 21, which forms one arm of the bell crank, may be adjusted in a simple and positive manner. The construction is such that the various members are subjected mostly to longitudinal stresses, particularly the bar 16.

Ample lubrication is provided, and the arrangement is such that the lubricating medium is not easily contaminated.

It will be clear that by selecting the relative positions of the shafts 5 and 12 and the curvature of the face 14 of the lever 13, a great variety of movements can be obtained.

It will be understood that certain features of this invention may be useful without regard to other features thereof and that sub-combinations may be used without including the entire mechanism. Such sub-combinations are, accordingly, a part of this invention. It is further obvious that various changes may be made, within the scope of the appended claims, in the details of construction without departing from the spirit of this invention. It is, therefore, to be understood that this invention is not to be limited to the specific details shown and/or described.

Having thus described the invention, what is claimed is:

1. Vibrating mechanism of the character described, comprising, a shaft having an eccentric thereon, means for driving said shaft, a lever pivoted adjacent said shaft and having a concave face engaging said eccentric, a bar slidably in said lever and adjustably clamped thereto and providing therewith a bell-crank, and a tension element pivoted to said bar to be reciprocated thereby.

2. Vibrating mechanism of the character described, comprising, a shaft having an eccentric thereon, means for driving said shaft, a roller on said eccentric having lubricating passages spirally thereof, a lever pivoted adjacent said shaft and having a concave face engaging said roller, a bar adjustably clamped to said lever and providing therewith a bell-crank, a pivot bracket adjustably mounted on said bar, and a tension element pivoted to said bracket to be reciprocated thereby.

3. Vibrating mechanism of the character described, comprising, a shaft having an eccentric thereon, means for driving said shaft, a roller having lubricating passages adapted to pick up lubricant and convey the same to its bearing, a lever pivoted adjacent said shaft and having a concave face engaging said eccentric, a bar adjustably clamped to said lever and providing therewith a bell-crank, a pivot bracket mounted on said bar, and a tension element pivoted to said bracket to be reciprocated thereby.

4. Vibrating mechanism of the character described, comprising, a shaft having an eccentric thereon, means for driving said shaft, a lever pivoted adjacent said shaft and having a face engaging said eccentric, a bar fixed to said lever and providing therewith a bell-crank, a housing for said mechanism providing an oil reservoir, a tension element connected to be reciprocated by said lever

and extending through a wall of said housing, and a partition in said reservoir adjacent said wall.

5. Vibrating mechanism of the character described, comprising, a shaft having an eccentric thereon, means for driving said shaft, a lever pivoted adjacent said shaft and having a face engaging said eccentric, a bar fixed to said lever and providing therewith a bell-crank, a housing for said mechanism providing an oil reservoir, a tension element connected to be reciprocated by said lever and extending through an opening in a wall of said housing, an adjustable cover for said opening, and a partition in said reservoir adjacent said wall.

6. Vibrating mechanism of the character described, comprising, a shaft having an eccentric thereon, means for driving said shaft, a lever pivoted adjacent said shaft and having a face engaging said eccentric, a bar fixed to said lever and providing therewith a bell-crank, a bracket adjustably mounted on said bar and having a pivot, a rigid member fixed to said lever and to said bracket in parallel relation to said bar, and a tension element pivoted on said bracket pivot to be reciprocated thereby.

7. Vibrating mechanism of the character described, comprising a supporting housing having bearings therein, a shaft mounted in said bearings, an eccentric on said shaft, a roller on said eccentric having a spirally arranged passage adapted to pick up lubricant and convey the same to its bearing, a lever pivoted adjacent said shaft and having a concave face engaged by said roller and a tension element connected to said lever to be reciprocated thereby, said housing being adapted to contain lubricant thru which said roller moves.

8. Vibrating mechanism of the character described, comprising a supporting housing having bearings therein, a shaft mounted in said bearings, an eccentric on said shaft, a roller on said eccentric having a spirally arranged passage adapted to pick up lubricant and convey the same to its bearing, a lever pivoted adjacent said shaft and having a concave face engaged by said roller, and a tension element connected to said lever to be reciprocated thereby, said housing being adapted to contain lubricant thru which said roller moves and having a partition adapted to divide the lubricant.

In testimony whereof I affix my signature this 8th day of November, 1928.

VICTOR E. FLANAGAN.

In testimony whereof I affix my signature this 6th day of November, 1928.
